UNITED STATES PATENT OFFICE.

OTTO LAUBER AND NORBERT KOCH, OF ESSEN-ON-THE-RUHR, GERMANY,
ASSIGNORS TO FRIED. KRUPP, OF ESSEN-ON-THE-RUHR, GERMANY.

WHEEL-BRAKE FOR GUN-CARRIAGES.

SPECIFICATION forming part of Letters Patent No. 770,178, dated September 13, 1904.

Application filed May 15, 1903. Serial No. 157,295. (No model.)

To all whom it may concern:

Be it known that we, OTTO LAUBER, residing at 36/2 Holsterhausen, and NORBERT KOCH, residing at 14 Kahrstrasse, Essen-on-the-Ruhr, Germany, subjects of the Emperor of Germany, have invented a certain new and useful Wheel-Brake for Gun-Carriages, of which the following is a specification.

The present invention relates to wheel-tire, 10 brakes of the type which is known to artillerists as a "Lemoine" brake. Such a brake is described on pages 135 to 141 and Plate VII, Figs. 1 to 4, of the work of Georg Kaiser, entitled *Konstruktion der Kriegs Fuhrwerke*, 15 published at Vienna in 1895. In this brake bands are passed from the arms which carry the brake-shoes over drums which are secured to the naves of the wheels to springs which for the purpose of applying the brakes may 20 be put under tension by means of a hand-lever or the like. By putting tension on the springs the bands, which normally pass loosely around the drums, are likewise tightened, so that they lie snugly to the drum-surfaces. If when the 25 parts are thus adjusted the gun runs back after a shot, the bands wind upon the drums in such a manner that the brake-arms are moved toward the wheel and the brake-shoes firmly pressed against the wheel-tire. In re- 30 turning the gun to battery the brake is automatically released by the unwinding of the bands upon the drums.

The Lemoine brakes heretofore known are subject to the disadvantage that the springs 35 employed require much space, not only because they must be bent to put them under tension, but also because the entire springs in thus bending change their position. These objections are avoided, according to the present invention, by introducing a torsional spring between the controlling device of the 40 brake and the brake-band.

One embodiment of this invention is shown 45 by way of illustration in the accompanying drawings, in which the brake is shown in use upon a gun-carriage with a drop or bent axle, in which drawings—

Figure 1 is a side elevation of this embodiment of the invention, together with those

parts of the gun-carriage which come under 50 consideration. Fig. 2 is a plan view of one-half of the carriage shown in Fig. 1. Fig. 3 is a front elevation of the carriage. Fig. 4 is a section on the line 4-4, Fig. 1, looking from the left. Fig. 5 is a detail view of a 55 portion shown in Fig. 3 on an enlarged scale. Fig. 6 is a section on the line 6-6, Fig. 5, looking from the right. Fig. 7 is a front view of another embodiment of the invention, several parts being shown in section. Fig. 8 60 shows a part of Fig. 7 on an enlarged scale. Fig. 9 is a section on the line 9-9, Fig. 8, looking from the right; and Fig. 10 is a section on the line 10-10, Fig. 8, looking from the right.

As already stated, the present wheel-tire 65 brake differs from Lemoine brakes heretofore known principally in that it has introduced between the controlling device of the brake and the brake-bands a torsion-spring instead of a bending spring. This torsion- 70 spring is suitably arranged in the hollow of the intermediate part E' of the drop-axle E E' in order to obtain a compact arrangement.

In the form illustrated in Figs. 1 to 6 the torsion-spring is shown as a wound or coiled 75 spring and consists of two parts G G' of equal length and opposite winding, Figs. 3 and 5. The inner ends of these spring parts engage in openings in a sleeve H. In the same manner the outer ends of these spring parts are 80 in connection with rings f' f''. Non-rotatably secured to the outer surface of the sleeve H is one end of a tube D, which surrounds the spring portion G. The tube D is rotatably mounted in a flange e', arranged on one face 85 of the axle part E', which flange is interrupted at two diametrically opposite points by segmental recesses e'', Figs. 5 and 6. Keyed to the end of the tube D, projecting beyond the axle part E', is a setting-lever B, the nave 90 b' of which, together with two segmental projections d', provided on the outer face of the tube D, lying on the inner side of the flange e', secures the tube D against axial movement. The interrupted flange e'' of the axial part E' 95 and the projections d' of the tube D constitute together a bayonet-joint which renders it possible to bring the tube D into the axial

part E', Figs. 5 and 6. The setting-lever B carries in a well-known manner a spring-operated pawl b², which stands in engagement with a toothed rack C, screwed concentrically with the axle part E' upon one of the carriage-cheeks A. The tooth-faces of the rack C are so inclined that they prevent, through the engaging pawl b², the swinging of the setting-lever B toward the muzzle of the gun-barrel. In the axle part E' within the spring portions G G' is arranged a shaft F, whose ends project beyond the axle part E' and are journaled in arms K, which are mounted upon the shanks E of the wheel-axle. The shaft F is guided loosely through the sleeve H and is centered, by means of its guide-rings f' f², on the one side in the tube D and on the other side in a flap e³ of the axle part E'. Rigidly connected with the ends of the shaft F upon the outer sides of the arms K are levers M, which have jointed connection with the ends of the brake-bands N, Fig. 1. The brake-bands N encircle, as in the well-known Lemoine brakes, drums P, which are fastened to the naves of the wheels. The other ends of the brake-bands N are in articulated connection with the brake-arms Q. The brake-arms Q consist of an inverted-T-section part q', on which the brake-shoes R are secured, and a forked portion, Fig. 4, the arms q² of which terminating in eyes are jointed to the cheeks of the carriage through the medium of bolts a' a² and bearings a³ a⁴. Each bearing a⁴ is in the form of a box and carries a coiled spring S, which encompasses the bolt a². One end of this spring engages the end of the fork-arm q² of the brake-arm Q, while its other end stands in connection with a shoulder a⁵ of the bolt a². The bolt a² is secured against turning by a projection a⁶, Fig. 1, on the shoulder a⁵, which projection enters a recess in the box a⁴. The spring S has initial tension and is so wound that it tends to throw the brake-shoes R away from the wheel-tires. In describing the manipulation and mode of operation it is assumed that the brake is to be moved from the position (not shown in the drawings) which the several parts assume when the brake is released. In this position the setting-lever B is in such position that its pawl b² engages in the outermost notch of the toothed rack toward the muzzle of the gun-barrel. The spring parts G and G' are relaxed, the brake-bands lie loosely about the drums B, and the brake-shoes are held away from the peripheries of the wheels by the springs S.

In order to apply the brake, the setting-lever B is thrown toward the trail of the gun. The movement of the setting-lever is transmitted through the tube D to the sleeve H and from the sleeve H through the spring parts G G' to the rings f' f², which cause a turning of the shaft F and the levers M. The latter turn at this time in the same direction

as the setting-lever B, so that they exert a pull upon the ends of the brake-bands N. In consequence the brake-bands now lie loosely on the peripheries of the drums P. The further throwing of the hand-lever B about the 7c position shown in Fig. 1 will then result in simultaneously putting tension on the spring parts G G' and laying the brake-bands tightly on the drums P, when the brake will be applied. If now the gun runs back on firing, 75 the bands will so wind upon the drums that the brake-arms Q under the tension of the springs S are moved toward the wheels and the brake-shoes will be pressed against the wheel-rims. 8c

By running the gun out to battery again the brake-bands unwind from the drums P, so that the brake-shoes R are removed from the wheel-rims by the springs S.

In order to take off the brake, the setting-lever B, after releasing the pawl b², is thrown toward the muzzle of the gun, so that the parts return to their starting positions. 85

The embodiment shown in Figs. 7 to 10 of the drawings differs from that above described only in that the torsion-springs G G' are replaced by a plate-spring T and the shaft F is omitted. The sleeve H in this embodiment is provided with a stay h', on which the plate-spring T is riveted. The ends of the 95 spring T are formed with trunnions, which are rotatable in the bearings K and carry on their free ends the levers M.

Having thus described the invention, the following is what is claimed as new therein: 10

1. In a brake for wheeled gun-carriages, the combination with the brake, and the winding means, of a torsional spring, a rotatable sleeve or tube surrounding the spring and connected therewith, and means adapted to be operated 10 to rotate the sleeve or tube to set the spring.

2. In a brake for wheeled gun-carriages, the combination with the brake, and the winding means, of a torsional spring, and a lever connected at one end to the spring and at the 11 other end to the winding means to cause a turning of the springs.

3. In a brake for wheeled gun-carriages, the combination with the brake, and the winding means, of a hollow axle extending transversely of the carriage, a torsional spring journaled in the hollow axle and connected with the winding means. 11

4. In combination with a gun-carriage constructed with a drop or bent axle, and having a brake, a winding-band for applying the same, and a setting-lever; the herein-described torsion-spring mounted in a hollow in the drop portion of the axle, and having connections with said winding-band and with the setting-lever. 12

5. In a wheeled gun-carriage, the combination of the brake, the means for setting the same, a winding drum and band for applying the brake, a torsion-spring interposed be- 13

tween the winding-band and the setting means, and the tube D surrounding a portion of said spring, connected with an intermediate point therein, and extending outwardly for connection with the setting means.

6. In a gun-carriage wheel-brake of the character described, the combination of the brake-arms, the winding drums and bands which move the brake-arms toward the wheels, the torsional spring-shaft connected with the bands to cause them to wind upon the drums, and means for applying a turning movement to said torsional spring-shaft, consisting of a hand-lever and a tube extending from the hand-lever over a portion of the torsional spring-shaft and connected with an intermediate point thereof.

7. In a gun-carriage, the combination of the axle, having a hollow drop portion, the tor-

sional spring brake-shaft mounted in said hollow drop portion, and projecting therethrough at opposite ends, arms suitably connected with the projecting ends of the torsional spring-shaft, winding-drums having bands connected at one end with said arms, brake-arms connected with the other ends of said bands, a tube extending into the hollow drop portion of the axle around one portion of the torsional spring-shaft, and connected to the middle point of the latter, and a setting-lever connected with said tube.

The foregoing specification signed at Düsseldorf, Germany, this 29th day of April, 1903.

OTTO LAUBER.
NORBERT KOCH.

In presence of—

PETER LIEBER,
WILLIAM ESSENWEIN.
